(57) **CLAIM**

We claim the ornamental design for an electronic cigarette,
as shown.

DESCRIPTION

FIG. 1 is a perspective view of an electronic cigarette
according to an embodiment.

FIG. 2 is a view of a first side of the electronic cigarette
depicted in FIG. 1.

FIG. 3 is a view of a second side of the electronic cigarette
depicted in FIG. 1.

FIG. 4 is a view of a third side of the electronic cigarette
depicted in FIG. 1.

FIG. 5 is a view of a fourth side of the electronic cigarette
depicted in FIG. 1.

FIG. 6 is a view of a first end of the electronic cigarette
depicted in FIG. 1.

FIG. 7 is a view of a second end of the electronic cigarette
depicted in FIG. 1.

FIG. 8 is a perspective view of an electronic cigarette
according to another embodiment.

FIG. 9 is a view of a first side of the electronic cigarette
depicted in FIG. 8.

FIG. 10 is a view of a second side of the electronic cigarette
depicted in FIG. 8.

FIG. 11 is a view of a third side of the electronic cigarette
depicted in FIG. 8.

FIG. 12 is a view of a fourth side of the electronic cigarette
depicted in FIG. 8.

FIG. 13 is a view of a first end of the electronic cigarette
depicted in FIG. 8; and,

FIG. 14 is a view of a second end of the electronic cigarette
depicted in FIG. 8.

1 Claim, 12 Drawing Sheets
